MATERIAL TREATING MACHINE

Louis Joseph Hruby, Cicero, Ill., assignor to
Western Electric Company, Incorporated, New
York, N. Y., a corporation of New York

Application December 10, 1930
Serial No. 501,205

4 Claims. (Cl. 91—55)

This invention relates to a material treating machine, and more particularly to a wire enameling machine.

It is an object of the present invention to provide a material treating machine wherein the possibility of eruption of the treating medium is minimized.

The invention is particularly applicable to wire enameling apparatus of the type that utilizes the heat of combustion of the solvents of a coating material as the sole medium for baking the coating material on the wire, and one embodiment contemplates the provision of a means positioned in the supply of coating material for preventing the coating material from being forcibly thrown out of the container due to sudden fluctuations in the gas pressure in the apparatus caused by premature ignition of the vaporized solvents of the coating material.

A better understanding of the invention will be had by reference to the following detailed description, taken in conjunction with the accompanying drawing, wherein

Fig. 1 is a front elevational view partly in section of a wire enameling apparatus embodying the features of the invention, and

Fig. 2 is a vertical sectional view taken along the line 2—2 of Fig. 1 in the direction of the arrows.

Referring now to the drawing wherein like reference characters designate the same parts throughout the several views, numeral 5 designates generally a supporting framework upon which is adjustably mounted a receptacle 6 provided with upwardly extending standards 7 and 8 in which is journaled the shaft of a sheave 12 to which a strand of wire 13 may be passed from a pulley 14 mounted on a shaft 16 supported independently of the remainder of the mechanism and driven by means not shown. The receptacle 6 is adapted to contain a supply of coating medium 17 composed of substantially non-combustible ingredients combined with suitable volatile, combustible substances. The coating medium is maintained at such a level relative to the sheave 12 that the wire 13 in passing around the sheave will be passed through the bath 17 of the coating medium. An upwardly extending portion 21 of the receptacle 6 supports a furnace designated generally by the numeral 20 in which the volatile combustible ingredients of the coating medium are ignited and burned to bake the substantially non-combustible ingredients of the coating medium on the wire or core.

The furnace 20 which will be described more

in detail hereinafter, has secured to the lower end thereof adjacent the sheave 12 a closure member 22 having downwardly extending teeth which extend into the grooves in the sheave so that upon rotation of the sheave, the coating medium 17 which is positioned in the receptacle 6 will form a seal which excludes outside air from a chamber 23 formed by the upwardly extending portion 21 of the receptacle 6, the sheave 12, and the closure member 22. Within this substantially air-tight chamber, the combustible solvents of the coating medium are volatilized or vaporized previous to their entrance into the furnace 20.

In the lower portion of the furnace 20 a heating tube 25 is positioned, through which the wire 13 being coated passes just prior to entering the combustion chamber 26 of the furnace 20. Secured to the outer surfaces of the heating tube 25 are electrical heating elements 27 which serve to heat the tube, thereby to complete the volatilization of the combustible solvents of the coating medium prior to its entering the combustion chamber 26, where the combustible gases formed by the volatilization of the coating medium are initially ignited by means of a spark plug 30. Upon being ignited the combustible substances of the coating medium will supply sufficient heat to bake the substantially noncombustible ingredients thereof upon the wire, the fumes of combustion being drawn off by a suitable exhaust system 31.

In wire enameling apparatus of the type described hereinbefore the ignition of the vapors of the solvents of the coating medium sometimes causes sudden fluctuations in the gas pressure in the combustion chamber which are transmitted downwardly to the supply of coating medium 17 in the receptacle 6 with sufficient force to cause some of the medium to be thrown forcibly out of the receptacle. At times in the operation of the machine explosions will also take place in the vaporizing chamber 23 due to the premature ignition of the vapors of the solvents of the coating material, also resulting in some of the coating medium being thrown out of the receptacle 6. In order to eliminate this danger there is provided a resilient baffle 33 which is V-shaped in cross-section and which has one leg thereof in engagement with the receptacle as indicated at 34, the other leg thereof resiliently engaging the peripheral surfaces of the sheave 12 as indicated at 35. The original shape of the baffle 33 is such that it must be compressed or sprung to bring it into the position shown in Fig. 2, with the result that the upper

leg of the V presses against the sheave 12 to maintain it in yielding engagement with the sheave. The baffle 33 is so positioned that the uppermost portion thereof at the apex of the V, as indicated by the numeral 36, is just below the surface of the coating medium 17 in the receptacle 6. The baffle is preferably formed of a material such as sheet steel of sufficient rigidity to enable it to resist the maximum gas pressures developed in the apparatus.

In the process of baking the enamel on the wire, a portion of the products of combustion, such as carbon and the like, which are not carried upwardly out of the baking chamber, settle downwardly on the coating bath and accumulate as sediment on the portion of the baffle lying on the base of the receptacle. This sediment may be readily removed from the bath by withdrawing the baffle from the receptacle and removing the sediment adhering thereto.

In the operation of the apparatus, the wire 13 is drawn from a supply (not shown), passed around the pulley 14, downwardly to the sheave 12 and through the coating medium, and thence upwardly through the vaporizing chamber 23, the heating tube 25, to the combustion chamber 26, where the volatile substances of the coating medium which have been vaporized are ignited by the spark plug 30, the heat generated by the combustion of the solvents being utilized to bake the remaining ingredients of the coating medium upon the strand of wire. A strand of wire may be passed around the pulley 14 and sheave 12 any desired number of times depending upon the thickness of the coating which it is desired to apply to the strand. In the event that the volatile substances of the coating medium are prematurely ignited in the vaporizing chamber 23 or that the ignition thereof in the combustion chamber occurs suddenly so that the gases of combustion tend to agitate the coating medium 17 and throw it out of the receptacle, such result is prevented by the baffle 33 which prevents agitation of the material adjacent the right side (Fig. 2) of the receptacle, due to the fact that it closes substantially all of the open space in the receptacle between the bottom of the sheave and the lower surface of the receptacle. The baffle 33 may be removed during the placing of the wire to be coated upon the pulley 14 and sheave 12

and may be removed or inserted at any time without interfering with the operation of the machine.

Although this invention has been described as relating to a coating apparatus wherein the solvents of the coating material are utilized to furnish the heat necessary to bake the substantially noncombustible ingredients of the coating compound on the wire, it is to be understood that the invention is applicable to other material treating mechanisms and the scope of the invention is to be limited only by the scope of the appended claims.

What is claimed is:

1. In a material treating apparatus, a container for a treating medium, a sheave positioned in the container for directing material through the medium, and a baffle positioned in the container under the surface of the medium and in yielding engagement with the sheave to prevent the medium from being discharged from the container. 90

2. In a material treating apparatus, a container for a treating medium having combustible ingredients, a sheave for directing material through the medium in the container, means for igniting the combustible ingredients of the medium to harden the other ingredients of the medium upon the material, and a V-shaped baffle positioned in the container below the surface of the medium, with one leg of the V yieldingly engaging the sheave for preventing the medium from being ejected from the container. 100

3. In an apparatus for treating material, a container for holding a supply of treating material, a combustion chamber for baking the material, and means associated with the container to prevent eruptions of the treating material therefrom, due to changes in gas pressure, said means extending into the bath and forming a receptacle in the bath. 110

4. In an apparatus for treating material, a container for holding a supply of treating material, a combustion chamber for baking the material, means removably secured to the container to prevent eruptions of the treating material therefrom, due to changes in gas pressure, and a member integral with said means extending over the bottom of the container. 120
